UNITED STATES PATENT OFFICE.

JULIUS SCHMOHL AND ERNST LAUSCHKE, OF CHICAGO, ILLINOIS, ASSIGNORS
TO BARNHART BROTHERS & SPINDLER, OF ILLINOIS.

DESIGN FOR A FONT OF PRINTING-TYPE.

SPECIFICATION forming part of Design No. 20,515, dated February 10, 1891.

Application filed December 31, 1890. Serial No. 376,406. Term of patent 14 years.

To all whom it may concern:

Be it known that we, JULIUS SCHMOHL and ERNST LAUSCHKE, subjects of the Emperor of Germany, residing at Chicago, county of Cook, 5 and State of Illinois, have invented and produced a new and original Design for a Font of Printing-Type, which is fully set forth in the following specification, reference being had to the accompanying typographical im- 10 pressions, forming a part thereof.

This design comprises upper and lower case letters, points, figures, dollar-mark, and character &. It is moderately condensed, the letters being composed of medium heavy un- 15 shaded lines. The general style of the letters is plain except as modified by the presence of somewhat peculiar ceriphs which are employed upon all terminals. In general, the ceriphs are oblique and terminate in at least 20 one fine point, having in many instances an opposite terminal less acute. In many of the letters, as capitals A, H, M, and N, the end of the line provided with an oblique ceriph is concave, the more acute point of what ap- 25 pears as a ceriph being in reality the terminal of the line itself thus hollowed out upon one side and provided at the other end of the concave cut with a slight spur, which appears

as the opposite end of the ceriph. Other ceriphs are simply oblique spurs projecting from 30 one side of the heavy line at the end, as in the case of lower-case y, j, and g at their terminals below the line. Other ceriphs are actual cross-strokes in oblique direction, as in the case of figure 2, lower terminal of capital 35 Q, and the ceriphs on the characteristics of E and F. In the majority of instances the line is slightly swelled at the end thus furnished with the complete ceriph, causing one end of the ceriph to appear less acute than the other; 40 but in some instances the ceriph consists merely of a fine cross-line without swell or shade projecting from one side, as in the case of the lower terminal of character & and characteristic of capital Q. 45

We claim—

The design for a font of type herein shown and described.

In testimony whereof we have hereunto set our hands, at Chicago, this 17th day of De- 50 cember, A. D. 1890.

JUL. SCHMOHL.
ERNST LAUSCHKE.
